ELECTRIC CABLE AND METHOD OF MAKING
SAME

Harry E. Thompson, Providence, R. I., assignor
to Anaconda Wire & Cable Company, New
York, N. Y., a corporation of Delaware

Application October 24, 1935, Serial No. 46,519

8 Claims. (Cl. 173—266)

This invention relates to cable and its method of production and more particularly to that type of cable which comprises a conductor or a plurality of conductors surrounded by insulating material and impregnated with liquid of good dielectric qualities such as oil, the whole structure enclosed in a lead sheath. It is well known that it is necessary to make some provision for the expansion of the impregnating medium with this type of construction since the increase of volume of the oil due to the heat liberated during operation of the cable will cause the lead sheath to expand to such a degree that recovery of the original dimensions will not follow the relief of pressure. When the flow of current in the cable is either diminished or discontinued the contraction of the oil upon cooling will form voids in the insulation, giving rise to ionization and eventually bringing about failure of the cable at that point. Heretofore, one known means for meeting the situation has been to provide reservoirs at the ends of the cable, or at intervals along its length to accommodate the increased volume of oil due to its expansion when heated, such oil flowing back into the cable upon the cooling thereof. Such old means are cumbersome and in a large installation the cost of the reservoirs and the necessary structures to accommodate them and related pipe connections and fittings becomes a matter of considerable moment. A further disadvantage arises due to the fact that the circulation of the viscous insulating liquid is very poor throughout a long tightly wrapped cable, even when special passages are provided for the purpose. Under such prior art conditions, there is frequently an appreciable time lag before the pressure built up at points remote from the reservoir is relieved by the expansion of the viscous liquid insulation into the reservoir. I am aware that, in a broad sense, it has been heretofore proposed to overcome the disadvantages inherent in oil impregnated or oil filled cables by the inclusion in the cable structure of expansible containers. But, such containers have of necessity been formed of thin flexible metal, which bends upon expansion and contraction of the medium therein. This is objectionable because fatigue will eventually disrupt the material. This is especially true when flexibility is dependent upon the metal parts being bent on a small radius.

Because of the deficiencies inherent in the prior art devices it is highly desirable to incorporate durable improved readily producible and easily assemblable means in the cable, which will com-

penstate for pressure variations set up by the expansion and contraction of the liquid or viscous insulation.

One feature of the invention contemplates the incorporation in the cable structure of such improved means for bringing about pressure compensation, which will avoid the disadvantages inherent in the devices of the prior art. Another feature of the invention relates to the novel method of production of the improved type of cable herein disclosed. A number of alternative specific embodiments of the invention are illustrated in the accompanying drawing.

In the drawing—

Fig. 1 is an enlarged detail view partly in elevation and partly in section illustrating one form of compensating device adapted to be incorporated in the improved structure; Fig. 2 is a view similar to Fig. 1, except that it shows a piston-like element adapted to be interposed between the closed end of the compensating device and the liquid insulation, which enters the open end of such device; Fig. 3 is a modified view similar to Fig. 2, wherein the piston-like element is in the form of a sphere; Fig. 4 is a modification illustrating a tubular compensating device divided into separate chambers along its length by transverse partitions and having parts through which the liquid insulation flows from the container into the reservoir; Fig. 5 is a cross section through a multi-conductor cable showing the improved containers incorporated in different locations in the cable structure; Fig. 6 is a view partly in elevation and partly in section showing a modified type of pressure compensating container; Fig. 7 is a view partly in elevation and partly in section illustrating the compensating container disposed helically around the oil impregnated insulation which envelopes the cable conductors; Fig. 8 is a side elevation illustrating a cable wherein the compensating container is laid up in a position corresponding to that normally occupied by one of the cable strands; Fig. 9 is a cross section on line 8—9 of Fig. 8; Fig. 10 is a cross sectional view illustrating a modification, wherein the conducting strands of the cable are laid up around a central core formed of a plurality of compensating tubular containers.

Referring first to the pressure compensation device illustrated in Fig. 1, 1 represents a tube of small bore which, as indicated at 2, is closed at one end and open at the opposite end, as indicated at 3. This tube has an internal diameter of such dimension that the oil or similar liquid insulation forming a meniscus will partially fill

the interior, thus leaving a cushion of gas between the closed end 2 and the meniscus defining the end of the body of insulation in the tube. During the cycles of operation, the expansion of 5 oil or other liquid insulation in the body of the cable will force a small additional quantity of the latter into the interior of the tube, thus building up a pressure of gas therein. Upon release of such built-up pressure, the oil will be again forced 10 into the cable insulation.

Where it is desirable to decrease the area of oil, which contacts with the gas cushion, I contemplate the provision of either a small substantially cylindrical piston, such as indicated at 5 in 15 Fig. 2, or a spherical element serving a similar function, such as indicated at 6 in Fig. 3.

While the invention may be embodied in a cable having incorporated therein one or more relatively short tubes, I also contemplate utilizing 20 a relatively long tube, as shown for example in Fig. 4, which is divided along its length into a plurality of separate chambers by interior partitions 8, each chamber having an opening 9 to permit the liquid insulation to pass to and 25 from one end of the chamber, such liquid insulation of course being adapted to exert a pressure on the gas cushion accommodated by the unfilled portion thereof.

My improved pressure compensating devices 30 may be incorporated in the cable structure in various ways. For example, as shown in Fig. 5, the devices 1 may be placed in the filler spaces 10 between the lead sheath 11 and the conductors 12. Similarly, a single tube 1^a may be placed in 35 the central void between the insulation of the several conductors.

It is also contemplated to employ a coiled compensating device, such as indicated at 1^b in Fig. 6. By the utilization of such a construction, it 40 is apparent that I can increase the volume of the gas cushion in a given length of cable without increasing the interior diameter of the capillary tube.

Fig. 7 illustrates a further alternative embodiment of the invention, wherein the pressure compensating device takes the form of a helical tube 1^c, which is spiralled about the body of insulation 14 surrounding a plurality of conductors, this tube being interposed between such 50 insulation and the lead sheath 11. In certain cases, I contemplate incorporating the improved pressure compensating means in the conductor itself. Such an arrangement is illustrated in Figs. 8 and 9, wherein 1^d represents a tubular element similar to that shown in detail in Fig. 4, this element being laid up in the cable in a 55 position corresponding to that normally occupied by one of the cable strands.

If the cable is to be used for the transmission 60 of high voltages, an arrangement such as illustrated in Fig. 10 is advantageous. In this embodiment of the invention, I provide a plurality of expansion tubes 1^e, which serve a dual purpose, because they also constitute a support for 65 the solid conducting strands 16. The latter are covered with suitable oil impregnated insulation 18, which in turn is enclosed by the lead sheath 11.

In this manner, a conductor of relatively large 70 diameter and small cross sectional area is made available without the introduction of wasteful voids.

Inasmuch as the improved cable disclosed herein is the first, so far as I am aware, to include liquid sealed gas containers, I was con- 75

fronted with the problem of devising a method whereby such containers could be first partially filled with the gas cushion and sealed with the liquid and subsequently incorporated in a cable to be impregnated with liquid insulating material. To meet this problem, I have devised a method of cable construction peculiarly well suited to the manufacture of cables, such as those disclosed herein, and such method constitutes one aspect of the present invention. 10

In making a cable embodying the improvements hereinabove disclosed, it is apparent that the gas in the tubes or other elements must be prevented from escaping while the tubes are being incorporated. Such escape of the gas is 15 prevented by the oil seal. An effective oil seal is secured by placing a number of tubes in a container, such tubes being of the character described having one closed end and one open end. The closed container, in which these tubes are 20 prepared, is made gas-tight and the air is exhausted therefrom. After such evacuation, an inert gas is admitted into the container at a pressure slightly less than that of atmosphere. This gas, of course, will enter the open ends 25 of the tubes, whereupon oil will be admitted and pressure within the container allowed to reach that of atmosphere. Thus, a small quantity of oil will be forced into the open end of each tube, thus producing the oil seal and 30 trapping a substantial volume of the cushioning gas between this body of oil and the closed end of the tube. The tubes are of such a size that the oil will be retained therein due to capillary action. Such small tubes are referred to 35 herein as capillary tubes.

The thus formed tubes are incorporated in the cable structure, so as to dispose them relatively to the conductors in other parts of the cable, as hereinabove set forth. The tubes or 40 gas cushion elements will usually be formed of relatively flexible metal, such as copper or copper alloy, or alternatively they may be of lead, block tin, or the like, although, generally speaking, copper, or its alloys, because of its 45 greater strength is usually to be preferred.

An important feature of novelty in my method is the procedure, whereby the gaseous cushion is trapped within the tubes, or other hollow elements by a liquid seal, so that the gas will not 50 escape while the tubes are being incorporated or assembled with the conductors. The impregnation of the insulated conductors may be accomplished in accordance with ordinary practice, for example, either by impregnating the paper insulation with suitable liquid dielectric, either before or after the conductors are enclosed in the lead sheath. Regardless of which practice is followed, it will be apparent that upon completion of the cable, the oil or other liquid insulating 55 medium will be permitted to react against the gaseous cushion trapped within the liquid sealed tubes or other hollow elements.

Referring now to some of the technical problems, which have presented themselves in the 65 evolution of the present invention; in the usual cable of the oil impregnated type, the quantity of oil required for complete saturation is approximately 55% of the volume enclosed by the lead sheath. The range of temperature during 70 operation may be taken as 60 degrees C. The mean coefficient of expansion for oil of this character is 0.00104 from which it follows that a cubic inch of oil at 10 degrees C. will occupy 1.0570 cubic inches at 70 degrees C. Therefore, in a 75

one foot length of cable which has a diameter under the sheath of two inches, the oil will increase in volume from 20.72 to 21.90 cubic inches during operation. Ten percent of this increase will be compensated for by the increase in diameter of the lead sheath leaving 1.06 cubic inches which must be provided for. If it is desired that the internal pressure shall not exceed forty pounds per square inch, the gas cushions in the expansion tubes must not be compressed more than three times their normal volume at 10 degrees C. and atmospheric pressure.

From this, it follows that if tubes 12 inches long are used the movement of oil within the tube can be 6.67 inches, if an oil seal of two inches is maintained at the open end. If the expansion chamber used has an internal diameter of 90 mils, each tube will absorb an expansion of 0.044 cubic inch without exceeding the stipulated temperatures and pressures. Twenty-five tubes will, therefore, serve the purpose. A preferable arrangement for the expansion tubes is illustrated in Fig. 10, in which it will be noticed that the tubes also serve as a support for the strands of the conductor, a construction which as previously stated is most efficient for the transmission of electrical energy at high potentials.

While the medium employed as a gas cushion is preferably inert and nitrogen or carbon dioxide may be mentioned for purposes of exemplification, it will be apparent that many other gases are entirely suitable for the purpose.

While I have described quite specifically certain embodiments of the invention illustrated and certain steps in the method of producing the improved cable, it is to be understood that the detailed features of the disclosure are to be interpreted in an illustrative rather than a limiting sense since various modifications may be made by those skilled in the art without departure from the scope of the invention as defined in the appended claims.

What I claim is:—

1. A cable comprising an insulated conductor enclosed in a fluid-tight sheath containing a liquid insulating medium, a capillary tube incorporated in the cable between the insulated conductor and the sheath and containing a gaseous cushion, said tube having a closure portion to prevent the escape of such gaseous cushion and having an opening to permit of an exchange of pressure reactions between the gaseous cushion and the liquid insulating medium due to volume changes of the latter incident to heating and cooling.

2. A cable comprising an insulated conductor enclosed in a fluid-tight sheath containing a liquid insulating medium and a capillary tube assembled between the conductor insulation and the sheath, said tube having a plurality of partitions sub-dividing it into a plurality of chambers each adapted to contain a gaseous cushion, there being an opening in each chamber so located with respect to said partitions as to permit an exchange of pressure reactions between the gaseous cushion of each chamber and the liquid insulating medium.

3. A cable of the character described comprising a lead sheath enclosing a conductor enveloped in paper insulation, a liquid insulating medium retained by the sheath and impregnating said paper insulation, a gas containing capillary tube assembled within the sheath between it and the conductor and having a port to permit of an exchange of pressure reactions between the gaseous cushion and the liquid insulating medium said element being a capillary tube of great flexibility to facilitate its assembly about the conductor.

4. A cable of the character described comprising an insulated conductor enclosed in an impervious sheath containing a liquid insulating medium, a flexible capillary tube forming a pressure compensation device assembled between the sheath and the conductor, said tube having a closure portion to retain a gaseous cushion and having a liquid sealed portion in open communication with the interior of the lead sheath so as to permit of an exchange of pressure reactions between the gaseous cushion and the liquid insulating medium.

5. A cable of the character described comprising an impervious sheath, an insulated conductor therein, a liquid insulating medium contained by the sheath for impregnating said insulation, a series of liquid sealed flexible capillary tubes assembled with the conductors and having gaseous cushions trapped therein, said tubes having portions in communication with the interior of the sheath to permit of an exchange of pressure reactions between the gaseous cushions and the liquid insulating medium.

6. A cable of the character described comprising a sheath of substantially inelastic metal enclosing an insulated conductor, a liquid insulating medium retained by the sheath, a pressure compensation device comprising a capillary tube subdivided to form a plurality of chambers each adapted to retain a gaseous cushion therein and each chamber having a port adapted to permit of an exchange of pressure reactions between the gaseous cushion and the liquid insulating medium, so as to compensate for changes in the volume of the liquid insulating medium incident to the heating and cooling thereof.

7. In the manufacture of insulated electric cables, the method which comprises evacuating a hollow flexible capillary element, admitting a gas thereto, trapping the gas in said element with a body of liquid insulating material forming a seal, assembling said element in juxtaposition to an insulated conductor, enclosing the assemblage within a sheath and introducing liquid insulation into said sheath.

8. In the manufacture of oil impregnated insulated cables, the method which comprises evacuating flexible capillary tubing closed at one portion and opened at another portion, trapping a gaseous cushion therein with a liquid retained within the tubes by capillary action, assembling such tubes with conductors surrounded by oil impregnated insulation and enclosing said parts within an impervious sheath.

HARRY E. THOMPSON.
